DESIGN FOR SHORTS OR SIMILAR ARTICLE

Herman M. McDonald, Evanston, Ill., assignor to Mac Dee Company, a corporation of Illinois

Application August 3, 1938, Serial No. 79,076

Term of patent 14 years

To all whom it may concern:

Be it known that I, Herman M. McDonald, a citizen of the United States, residing in Evanston, in the county of Cook and State of Illinois, have invented a new, original, and ornamental Design for Shorts or Similar Article, of which the following is a specification, reference being had to the accompanying drawing, forming part thereof.

Figure 1 of the drawing is a front view of shorts or similar article, in a flattened condition, embodying my design; and Figure 2 is a rear view of the flattened garment shown in Figure 1.

I claim:

The ornamental design for shorts or similar article, as shown.

HERMAN M. McDONALD.
